UNITED STATES PATENT OFFICE.

WILLIAM C. WOLFE, OF HAGERSTOWN, MARYLAND.

PORTABLE STEAM-ENGINE.

SPECIFICATION forming part of Letters Patent No. 284,701, dated September 11, 1883.

Application filed June 20, 1883. (No model.)

To all whom it may concern:

Be it known that I, WILLIAM C. WOLFE, of Hagerstown, in the county of Washington and State of Maryland, have invented certain new and useful Improvements in Steam-Engines; and I do hereby declare the following to be a full, clear, and exact description of the invention, such as will enable others skilled in the art to which it pertains to make and use it, reference being had to the accompanying drawings, which form part of this specification.

My invention relates to an improvement in steam-engines, especially in that class which are known as "portable engines;" and it consists, first, in the combination of the engine-frame having the cylinder and the saddle secured to its ends, and supported upon the bracket at one end, the engine being provided with flanges, between which the cross-head moves, the engine and bracket being tongued and grooved together, so as to prevent any lateral movement of the bed-plate; second, in the engine-frame, which is provided with horizontal flanges upon one side, and which are connected together by a cross-flange, with the feed-pump, which is secured to the cross-flange in a line with the slide-valve; third, in the combination of the engine-frame having the steam-cylinder attached to one end, a suitable bracket secured to the boiler, the steam-chest attached to the cylinder, and a brace having a stud or projection which catches in a recess in the end of the steam-chest, whereby the cylinder is prevented from becoming laterally displaced, but is allowed to expand and contract from the variations in the chamber without injury to any of the parts; fourth, in a saddle which supports one end of the engine-frame, and which has its two bearings for the crank and eccentric shaft, and space enough around it to allow a stepped pulley to be secured to the shaft for the purpose of operating the governor, and which pulley allows a greater variation in the speed of the governor.

Figure 1 is a side elevation of an engine embodying my invention. Fig. 2 is a plan view of the same, partly in section. Fig. 3 is a side elevation of the engine-frame, showing the feed-pump and valves in section. Fig. 4 is a vertical cross-section, taken upon the dotted lines of Fig. 3, of the engine-frame. Fig. 5 is a per-

spective of the brace which is connected to the steam-chest. Fig. 6 is a side elevation of the brace, shown in connection with the steam-chest. Fig. 7 is an end view of the saddle and 55 the stepped pulley.

A represents the engine-frame, which has the steam-cylinder B secured to it at one end, and the saddle C at the other. This engine-frame is supported at the end to which the cylinder is attached by means of the bracket D, which is secured rigidly to the side of the boiler, as shown in Fig. 1, and which bracket has a suitable tongue formed upon its top, so as to fit in a corresponding groove in the end of the engine-frame, for the purpose of holding these two parts in line with each other. In order to still further prevent any lateral displacement of the cylinder and its steam-chest E, there is rigidly bolted to the boiler the brace 60 F, which has a stud or projection, G, extending horizontally from its upper end. This stud G catches in a recess in the end of the steam-chest E, and serves to help to hold the steam-chest and cylinder in their proper position. Owing to the heat from the boiler, the different parts will expand and contract differently. When the brace is secured in position upon the cold boiler, it is placed closely in contact with the steam-chest, and as the boiler 65 expands from the heat this brace F gradually moves back from the steam-chest, as shown in Fig. 6. This outward movement of the brace F allows the different parts to expand endwise without the twisting or injury to the different 70 parts which would inevitably ensue were no provision left for this movement.

Upon the outer side of the engine-frame are formed the horizontal flanges H, beveled at the sides or edges, as shown, which have the 75 guiding-ribs formed as a part thereof, and which have wide bearing-surfaces J for the adjustable gibs of the cross-heads. These bearing-surfaces are shaped to correspond to the shape of the gibs, so that as the gibs and 80 bearing-surfaces wear away the gibs adjust themselves uniformly upon the sides, as well as upon the bottom of the flanges. In order to catch the waste or overflow, both from the feed-pump and from the stuffing-box of the 85 cylinder-head, there are formed suitable grooves in the lower flange, so as to catch all 90 95 100

of this waste or overflow and conduct it directly into the oil-cups K, as shown in Fig. 1. These cups, by catching all the waste oil and water, serve to prevent the parts from being overflowed, and the engine from having a dirty slovenly appearance. Upon the opposite side of the engine-frame A, near the saddle C, are formed the nearly-horizontal flanges L, which are united together by means of a vertical or cross flange, M. In between these nearly-horizontal flanges is placed the feed-pump N, which has its inner end provided with a screw-bolt or stud, which passes back through the flange M, so as to receive a nut or other tightening device, for the purpose of securing the pump rigidly in place. The hole through the flange M for the stem from the rear end of the pump to pass through is made oblong, so that the pump will have a slight vertical movement, so as to allow it to be moved by means of the clamping-nut Q. The water passes up into the air-chamber and down through the passage V, which is cast in the engine-frame A, and through the pipes W, and thence into the heater X. This feed-pump N and the slide-valve Y are placed upon a direct line with each other, and they are connected together by the rod Z. Through the engine-frame A is made an opening, A', through which the inner end of the eccentric-rod B' connects directly with the slide C', which is connected to the center of the rod Z. As the eccentric moves back and forth it operates the feed-pump N and the slide-valve Y at the same time, thus dispensing with a number of parts, and simplifying and cheapening the construction of the engine accordingly. By the location of the feed-pump and the air-chamber upon the engine-frame A, and at a distance from the steam cylinder and boiler, not only is the feed-pump placed in a direct line with the slide-valve, but it is placed upon the coolest part of the engine, so that there is little danger of the heat converting the feed-water into steam, and thus interfering with the action of the pump.

The heater X consists of a large pipe, through which the exhaust-steam passes, and which exhaust-steam heats the feed-water on its passage to the boiler.

The saddle C, which is rigidly secured to one end of the engine-frame A and to the top of the boiler, is provided with the two bear-

ings J', for the crank and eccentric shaft, and in between these two bearings is left a space 55 sufficiently large for the eccentric and the stepped pulley L'. This pulley L' is intended to be used in running the governor, and allows a greater variation to the speed to which the governor is run than can be done by the usual construction of the parts. By placing this pulley L' in the position shown the parts of the engine are greatly simplified and cheapened, and less space is taken up. Upon the edges and ends or flanges for bolting the saddle to the boiler are formed the grooves O', to catch the oil from the journals J', and prevent it from running upon the boiler.

Having thus described my invention, I claim—

1. The combination of the engine-frame A, having the cylinder B and the saddle C secured to its ends, and supported upon the bracket D at one end, the engine-frame being provided with the flanges H, between which 75 the cross-head moves, the engine-frame and bracket D being tongued and grooved together, so as to prevent any lateral movement of the bed-frame, substantially as shown.

2. The engine-frame A, provided with the 80 flanges L M, with the feed-pump and its attachments, the feed-pump being secured directly to the flange M, substantially as described.

3. The combination of the engine-frame, the 85 cylinder B, steam-chest E, the bracket D, and the brace F, provided with the stud or projection G, the parts being arranged substantially as set forth.

4. The combination of the engine-frame A, 90 having the opening A' through it, the eccentric-rod B', the slide C', and the rod Z, and the feed-pump and slide-valve placed in a direct line with each other, substantially as described.

5. The saddle C, provided with the two bearings J', with the crank and eccentric shaft, provided with the stepped pulley L', placed between the bearings J', substantially as set forth.

In testimony whereof I affix my signature in presence of two witnesses.

W. C. WOLFE.
